UNITED STATES PATENT OFFICE.

GEORGE C. TAFT, OF WORCESTER, MASSACHUSETTS, ASSIGNOR TO THOMAS H. DODGE, OF SAME PLACE.

IMPROVEMENT IN SCREW-WRENCHES.

Specification forming part of Letters Patent No. **55,739**, dated June 19, 1866.

To all whom it may concern:

Be it known that I, GEORGE C. TAFT, of the city and county of Worcester, and State of Massachusetts, have invented certain new and useful Improvements in Wrenches; and I do hereby declare that the following is a full, clear, and exact description of the same, reference being had to the accompanying drawings, forming a part of this specification, in which—

Figure 1 represents a side view of my improved wrench; and Fig. 2 represents a longitudinal central section on line A B, Fig. 1, looking in the direction of arrow 1.

In the drawings, A represents the stationary jaw connected with the bar B and shank C, the latter receiving the handle in the usual manner.

D represents the movable jaw, which works upon the bar B.

E represents the cylinder-nut, by which the jaw D is operated by means of the female screw-thread *a* of nut E taking into the male screw-thread *b* on the bar B.

The rear part F of jaw D is turned or cast so as to leave a shoulder, *c*, against which the front of nut E bears when the wrench is used.

The front part of nut E is cored out, as seen at *d*, but a flange, *e*, is left about midway. The front of the flange is beveled off, as seen at 1, while the rear part has a perpendicular edge, as seen at 2.

A stirrup, *f*, projects back from jaw D, and is sprung past the flange *e* on nut E, so that when

jaw D and nut E are arranged in position upon bar B, as shown in the drawings, they are securely locked together, whereby, as nut E is turned back, it will withdraw jaw D, while when nut E is turned forward it bears against shoulder *c* and forces jaw D forward.

It will be observed that stirrup *f* is subject to but little strain in withdrawing the movable jaw, and none when the wrench is used to turn a nut, the jaws being held in place, its shoulder *c* bearing against the front of nut E.

The rear end, *g*, of stirrup *f* may be beveled on both edges, if desired, only one edge, 3, being shown beveled in the drawings.

I have shown but one stirrup, but two or more may be used, if desired, although one answers a good purpose for the smaller-sized wrenches.

Having described my improved wrench, what I claim therein as new, and desire to secure by Letters Patent, is—

1. The combination, with nut E, having a flange, *e*, of the jaw D and its stirrup *f*, substantially as set forth.

2. The combination, with the front of nut E, of the shoulder *c* on jaw D, as and for the purposes set forth.

3. Beveling off the front of flange *e*, in combination with beveling off the rear of stirrup *f*, as seen at 3 in the accompanying drawings.

GEO. C. TAFT.
